UNITED STATES PATENT OFFICE.

MARVIN L. CRANNELL, OF TROY, NEW YORK.

NEEDLE-THREADER.

SPECIFICATION forming part of Letters Patent No. 760,427, dated May 24, 1904.

Application filed July 29, 1903. Serial No. 167,503. (No model.)

To all whom it may concern:

Be it known that I, MARVIN L. CRANNELL, a citizen of the United States, residing at Troy, in the county of Rensselaer and State of New York, have invented new and useful Improvements in Needle-Threaders, of which the following is a specification.

This invention relates to means for threading sewing-machine needles, and has for its object to provide improved means of this character in the nature of an attachment for convenient application to the stationary arm of any ordinary sewing-machine in position for convenient manipulation to facilitate the threading of the needle. It is furthermore designed to provide for conveniently applying and removing the device without changing or altering any part of the sewing-machine whatsoever and also to arrange for readily adjusting the device to an inoperative position when not in use, so as not to interfere with the ordinary manipulation of the sewing-machine, thereby obviating the necessity for entirely removing the attachment when not actually in use for threading the needle.

With these and other objects in view the present invention consists of the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a side elevation of a portion of a sewing-machine arm having the device of the present invention applied thereto and shown in its initial threading position. Fig. 2 is a similar view showing the device adjusted to its final threading position. Fig. 3 is a detail perspective view of the attachment removed from the machine. Fig. 4 is a longitudinal sectional view thereof. Fig. 5 is a detail sectional view on the line 5-5 of Fig. 4. Fig. 6 is a detail sectional view through the handle of the device to show the mounting of the thread-engaging hook.

Like characters of reference designate corresponding parts in each and every figure of the drawings.

The present embodiment of my invention consists of a body or bracket made up of front and rear plate members 1 and 2, respectively, which are riveted or otherwise mutually connected. The inner face of one of the members, preferably the member 2, is provided with an intermediate longitudinal groove or way 3, extending throughout the entire length of the member and open at opposite ends. The lower end of the bracket is provided with a concaved socket or seat 4, intersecting the lower end of the groove. At an intermediate point the front face of the front member 1 is provided with a transverse seat or recess 5, intersecting the opposite edges of the member and receiving a cross-bar 6, which is riveted or otherwise connected to the bracket and has its opposite ends projected beyond the bracket and provided with perforations 7 for the reception of fastenings to secure the device in place, as will be hereinafter described.

Working in an endwise direction through the longitudinal groove or way 3 is an arm 8, which projects through the opposite ends of the way and preferably consists of a thin metallic and elastic strip capable of sliding through the way and having a frictional engagement with the walls thereof sufficient to hold the strip or arm against the action of gravity, so as to prevent the same from dropping out of the bracket.

At the lower end of the flexible or elastic arm there is a handle 9 projected rearwardly from the arm and provided in its front end with a longitudinal socket 10 for the reception of the shank portion of a hook 11, which is held against displacement by means of a suitable set-screw 12, piercing the handle and engaging the shank of the hook.

For an understanding of the application and operation of the present invention reference is had to Figs. 1 and 2 of the drawings, wherein I have illustrated a portion 13 of any common or ordinary sewing-machine arm, which carries in the usual manner the vertically-reciprocating needle-bar 14, to which is connect-

ed an ordinary needle 15. The bracket or body of the present device is applied to the rear or under side of the sewing-machine arm and is connected thereto by means of suitable 5 screws, one of which has been indicated at 16, passing through the openings 7 of the ears formed by the opposite ends of the cross-bar 6. It will here be observed that the attaching-bracket is of convolute form, so as to fit 10 in the angle between the horizontal and upright portions of the sewing-machine arm, and it will therefore be understood that the shape or form of the bracket may be considerably varied to accommodate it to the various forms 15 of arms without departing from the spirit of the invention.

In using the present device the handle 9 is grasped and drawn downwardly, so as to pass the hook 11 through the eye of the needle, 20 after which the thread 17 is engaged with the hook, and then the handle is drawn rearwardly, so as to withdraw the hook with the thread through the eye of the needle. It will now be understood that the arm 8 is flexible 25 or elastic, so as to permit of the lateral movements necessary to pass the hook 11 through the eye of the needle and withdraw the same therefrom. Furthermore, the bill portion of the hook should stand upright or rise from 30 the shank thereof in order that the thread may be conveniently engaged therewith merely by placing the same transversely across the upper side of the shank and then withdrawing the hook through the eye of the needle, where- 35 by the thread will lie in the path of the hook and be carried therewith through the needle-eye. When not in use, the arm is moved upwardly to its upper limit, with the front portion of the handle 9 and the hook lying within 40 the seat or socket 4 in the lower end of the bracket, whereby the device is disposed so as not to interfere with the usual manipulation of the machine, and the hook is housed and protected against damage by accidental contact with the sleeve or hand of the operator. 45

From the foregoing description it is apparent that the device of the present invention is very simple and inexpensive and is complete in itself. Moreover, it is in the nature of an 50 attachment and is capable of application to the arm of any sewing-machine without requiring any change or alteration whatsoever in the arm or any other part of the machine and when in place does not interfere with the 55 proper manipulation of the sewing-machine.

Having thus described the invention, what is claimed, and desired to be secured by Letters Patent, is—

1. A needle-threader embodying an attaching-bracket having a way, an arm slidably mounted in the way and projected beyond one end of the bracket, said arm being flexible to permit lateral play of its projected portion, and a thread-engaging device carried by the

projected portion of the arm and of a size and 65 form to be entered through and withdrawn from the eye of a needle.

2. A needle-threader embodying an attaching-bracket made up of a pair of members placed face to face, the contiguous face of one 70 of the members being provided with an open-ended groove, an arm working in the groove with one end projected therefrom and flexible to permit lateral play thereof, and a thread-engaging device carried by the projected portion of the arm. 75

3. A needle-threader embodying an attaching-bracket, an arm slidable endwise thereon with one flexible end portion projected beyond the bracket, a thread-engaging hook carried 80 by and projected laterally at one side of the flexible portion of the arm, and a handle carried by and projected laterally at the opposite side of the arm, whereby the arm may be slid in an endwise direction and also moved laterally to bring the hook into and out of operative position and also to move said hook into and out of the eye of the needle. 85

4. A needle-threader embodying an attaching-bracket having an open-ended and otherwise closed way extending entirely therethrough, a spring-arm mounted to slide through the way and having a frictional engagement with the walls thereof to adjustably hold the arm, the lower end of the arm capable of being projected below the bracket and moved laterally, a handle carried by the lower portion of the arm and projected at one side thereof, and a thread-engaging hook carried by and projected at the opposite side of the 100 arm. 95

5. A needle-threader embodying an attaching-bracket having a seat, an arm movable endwise upon the bracket and across the seat with one flexible end portion capable of being 105 projected beyond the bracket, and a thread-engaging device carried by the flexible end portion of the arm and capable of being moved therewith into the seat to be housed thereby when not in use. 110

6. A needle-threader embodying an attaching-bracket having an open-ended way therein and provided with a recess or seat intersecting one open end of the way, an arm slidably mounted in the way with one flexible end portion projected outwardly through the recess, and a laterally-projected thread-engaging hook carried by the flexible portion of the arm and movable therewith into the recess or seat to be housed thereby when not in use. 115 120

7. A needle-threading device for sewing-machines, embodying an attaching-bracket having a longitudinal way extending therethrough and provided with a seat or recess intersecting the lower open end of the way, a 125 spring-strip forming an arm slidably mounted in the way and capable of being projected through the lower open end thereof, a handle

carried by the lower end of the arm and projected at one side thereof with a socket formed in its inner end, and a thread-engaging hook having its shank fitted within the socket of the handle and projected at the opposite side of the arm, the hook being movable with the arm into the seat or recess of the bracket to be housed thereby when not in use.

In testimony whereof I have signed my name to this specification in the presence of two subscribing witnesses.
